UNITED STATES PATENT OFFICE.

WILLIAM D. GHARKY, OF PHILADELPHIA, PENNSYLVANIA.

TELEPHONE SYSTEM.

SPECIFICATION forming part of Letters Patent No. 626,462, dated June 6, 1899.

Application filed December 24, 1898. Serial No. 700,199. (No model.)

To all whom it may concern:

Be it known that I, WILLIAM D. GHARKY, a citizen of the United States, residing in the city and county of Philadelphia, State of Pennsylvania, have invented certain Improvements in Telephone Systems, of which the following is a specification.

My invention relates to telephone systems, and particularly to the arrangement and operation of what are known as "multiple-station" or "many-party" lines.

It has for its object the provision of improved means whereby a number or all of the stations on any line may send and receive signals to and from each other and to and from a central office, the signaling-circuits being separate and distinct from the metallic talking-circuits in part or in whole, yet requiring only the usual pair of wires for their operation.

In another application filed concurrently herewith, Serial No. 700,200, I have illustrated and described an arrangement similar in principle to that hereinafter set forth; but in that case the connections and arrangement are such that the central station only can call the substations, while the substations can call central, but not each other. The present application is not concerned with such a construction specifically, although, broadly speaking, it is covered by the claims in the other case.

Stated generally, my present invention contemplates the provision of a bridge or bridges across the metallic circuit which may or may not constitute a portion of the subscriber's ordinary apparatus. These bridges contain more or less impedance—such, for instance, as properly-wound coils having closed magnetic circuits—but preferably the bridges include parts of the ordinary talking apparatus, such as the secondary winding of the induction-coil. In any case the middle point of each bridge in an inductive sense is connected to ground through proper signaling apparatus. Thus if there are a number of stations on the same metallic circuit any one of them may call the others, and even if conversation is going on no substantial interruption thereof will take place. The arrangement has many advantages besides this which scarcely need mention. Induced currents or static effects

will be dissipated without affecting any talking apparatus, while the multiplied conductivity of the line for signaling-current enables more subscribers to be thus grouped than would be possible with a series arrangement of the line-wires.

The accompanying drawings illustrate my invention, the same letters and figures of reference therein referring to the same parts throughout.

In the drawings, Figure 1 is a diagram showing a two-station arrangement only, it being understood that these stations stand for a much larger number. Figs. 2, 3, and 4 are diagrams of slightly-modified substation-circuits.

Referring to Fig. 1, X and Y are two subscribers' stations having in common the line-wires 1 and 2. It will be understood that in practice there will be anywhere from two to twenty or more substations like these connected to the same circuit; but for the purposes of illustration it is sufficient to show these two, as the others would all be duplicates thereof. R at station X is an ordinary telephone-receiver, included in a bridge 3 3 between the two line-wires 1 and 2. 1 is the secondary winding of an induction-coil, similarly included in a bridge 4 4. From the middle point of this secondary winding a wire 6 is taken off and conducted to the ringer Q, then to the generator G, and thence to ground. 5 designates the local circuit, containing the transmitter, the primary winding *i* of the induction-coil, the hook-switch H, and the battery *b*. The generator is preferably provided with the usual push-button or automatic shunt, which while it is not being operated virtually removes its resistance and impedance from the line. We thus have in a long line of, say, thirty substations, such as a country toll-line, a signaling-circuit of only one-quarter the total resistance of the metallic circuit, together with the full complement of ringers, all in parallel with each other and all responsive, of course, to any signaling-current passing along the line. A very great advantage in this arrangement over the ordinary bridging bell systems resides in the fact that it is not necessary to wind the ringers for high impedance. Their resistance may vary

through quite a wide range without at all affecting the efficiency of this system, the only requisite being that their relative resistances shall be such that the nearer ones will not 5 take current to the exclusion of farther ones in any case.

In Fig. 2 I have shown the ringer and the generator in separate ground-taps, the ringer being included in the wire 6, leading out from 10 the inductively central point of the induction-coil I, while the generator is included in a wire 7, leading out to ground from the middle point of the windings of the receiver R.

In Fig. 3 I have shown both the ringer and 15 the generator in the wire 7 from the middle point of the receiver-windings, while in Fig. 4 the ground-wire 7 leads from the middle point of the secondary winding I, and two receivers are included in the same bridge with 20 the secondary for the purpose of obtaining a balance.

Many other arrangements might be suggested which would give the desired results. Thus I might connect an ordinary impedance-coil, as shown at the right of Fig. 4, 25 across the line-wires 1 and 2 and ground the middle point of its windings through the signaling instruments. I prefer, however, to have as few bridges across the metallic circuit as possible, inasmuch as each bridge adds 30 another path, however limited, for leakage of voice-currents.

I am aware that it is not new to utilize the two sides of a metallic circuit in parallel for 35 signaling, nor is it new to utilize the coils of working apparatus in a differential as well as a cumulative relation. I do not, therefore, claim such arrangements broadly, but I believe that it is original with me to provide 40 parallel signaling branches at a number of

stations in connection with a main circuit utilized in this manner.

What I claim, and desire to secure by Letters Patent of the United States, is—

1. A multiple-station telephone-circuit composed of two conductors adapted to be used in common by all the stations for talking purposes, telephones at all the stations adapted to be connected to the two conductors, a generator of signaling-current and a ringer, at 45 each station, connected on one side to both conductors through bridged impedance, and on the other side to ground, substantially as described.

2. A multiple-station metallic telephone- 55 circuit having coils of high impedance bridged across the metallic circuit at the various stations, conductors connecting the inductively middle points of said bridges with the ground, signal-receiving devices normally included 60 in said ground-conductors, and generators of signaling-current adapted to be also included in said ground-conductors, substantially as described.

3. A multiple-station metallic telephone- 65 circuit having at each station two bridges containing impedance, and a conductor connecting the inductively middle point of each of said bridges with the ground, a signal-receiving instrument connected to respond to 70 current in one of said ground-conductors, and a generator arranged to send signaling-current through the other of said ground-conductors to the line, substantially as described.

In testimony whereof I have hereunto set 75 my hand this 21st day of December, 1898.

WM. D. GHARKY.
